SCAVENGING OF RADIOACTIVE AEROSOLS
Jan Rosinski, Cicero, and Donald K. Werle, Franklin Park, Ill., assignors to the United States of America as represented by the United States Atomic Energy Commission

No Drawing. Filed May 11, 1961, Ser. No. 109,467
6 Claims. (Cl. 55—84)

This invention deals with the precipitation of radioactive suspended material from the atmosphere. The problem of decontaminating atmospheres from radioactive aerosols arises after a nuclear accident in a reactor, and it also becomes important for treating radioactive atmospheres released by nuclear-powered ships.

It is an object of this invention to provide a process by which radioactive aerosols of the type described above can be precipitated in a comparatively fast and quantitative manner.

It is a further object of this invention to provide a process for the precipitation of radioactive aerosols which does not require a complicated apparatus.

A great number of gaseous and liquid precipitating agents were investigated for the removal of radioactive aerosols, but found unsatisfactory; silicon tetrafluoride, however, proved to be well qualified. It was found that, while silicon fluoride improves the precipitation of the aerosols, a mixture of it with water is still more effective. An explanation of the outstanding suitability of silicon tetrafluoride for the purpose of this invention cannot be given.

The process of this invention thus comprises introducing silicon tetrafluoride with or without water into the atmosphere to be treated and removing the precipitated substance from the atmosphere.

The quantity of silicon tetrafluoride may vary widely; amounts as low as 0.044% by volume have been found to have a pronounced beneficial effect on the settling time of the radioactive aerosol. The most advantageous quantity of water is that between 1.5 and 3% by volume as referred to the amount of silicon tetrafluoride added.

Because silicon tetrafluoride has a tendency to hydrolyze in the presence of water and because the hydrolyzation products have corrosive and toxic properties, it was found advisable to add a neutralizing agent to the

2

silicon tetrafluoride. The neutralization agents best suitable were sodium metasilicate and sodium hydroxide; they are preferably added in the form of a dilute aqueous solution, so that a separate addition of water is not necessary. The concentration of these solutions may range from 1 to 2 M. Instead of mixing the neutralization agent with the silicon tetrafluoride, it can be introduced also shortly after the silicon tetrafluoride has been added.

In order to study the effect of various substances on the behavior of aerosols, a radioactive atmosphere was artificially created. For this purpose a gold wire was neutron-bombarded and mounted in an about 21-inch high Lucite chamber, the inside walls of which had been coated with a conducting antistatic compound. The wire was mounted between gold electrodes, and the chamber was closed and slightly evacuated to about 28 inches of Hg absolute pressure. An electric current of 6000 volts was then discharged through the wire whereby the latter exploded and disintegrated into minute particles. After the explosion, filtered air was admitted to the chamber; it took from 2 to 3 minutes until the pressure had reached one atmosphere. After this the chamber was closed again.

The chamber had a window 6 inches above the bottom, through which the radioactivity could be viewed and measured by means of a scintillation counter and recorded with a scintillation spectrometer. Of course, as the aerosol coagulated and settled to the bottom, the radioactivity in the upper space of the chamber decreased. The background activity was also measured in each case and deducted from the readings in the chamber.

The following Example I gives a comparison of various scavenging gases.

EXAMPLE I

A radioactive gold aerosol was prepared in each run as described above. The sedimentation rates were measured from time to time by determining the radioactivity at the level of the window of the chamber; these measurements were used for calculating the time when the radioactivity had reached a value of 90, 80, 70, 60, 50, 40, 30, 20 and 10%, respectively. The conditions used and the results of the calculations from the measurements, expressed in minutes after the exposure, are compiled in Table I.

Table I

Expt. No.	I	II	III	IV	V	VI	VII	VIII	IX	X	XI	XII

Scavenger used, v/o	None	0.153 (C ₂ H ₅) ₂ O, 0.153 SiF ₄	0.153 NH ₃	0.153 NH ₃	0.153 SiF ₄	0.044 SiF ₄	0.153 NH ₃ excess HCOOH vapor	None	Fine water spray	Coarse water spray	Fine water spray 0.044 SiF ₄	Coarse water spray 0.044 SiF ₄
Radio-activity, percent:												
90	53	33	4.00	23	36	7.00	8.99	27	21	30	3.50	3.50
80	70	42	6.00	26	41	8.60	11.28	45	34	39	4.99	4.99
70	85	47	7.00	28	46	10.19	12.98	65	43	51	5.70	6.20
60	102	51	7.18	32	49	11.98	13.99	87	49	63	6.20	7.20
50	124	55	7.54	35	54	13.99	16.03	107	56	75	6.50	8.50
40	147	59	8.30	41	60	16.03	18.75	127	62	92	6.70	10.50
30	177	64	10.50	48	67	19.23	25.00	155	74	113	7.50	12.21
20	217	72	15.50	60	81	24.51	37.13	106	92	135	8.99	14.48
10	404	97	30.99	85	130	37.13	53	210	120	178	13.49	24.51

It will be seen from Table I that the gold used for all experiments had been irradiated with 1 mc., with the exception of experiment VIII where the gold had been exposed to 16 mc. The least effective scavengers were those used without water and those of a non-hygroscopic nature, such as ammonium chloride (experiment V) and boron trichloride-ethylene oxide mixture (experiment II). Hygroscopic scavenging agents were found to be superior in all cases. By far the best results were obtained with silicon tetrafluoride used in combination with a fine water spray, less than 14 minutes being required for a 90% precipitation.

Because hydrolysis products of silicon fluoride proved to be corrosive, replacement of this scavenging agent by the hygroscopic ammonium formate was investigated. However, ammonium formate proved only about half as effective as silicon tetrafluoride of the same concentration, as will be obvious from a comparison of experiments VII and III.

The effect of degree of radiation exposure was also determined in carrying out experiment VIII with a gold aerosol having received 16 mc. and comparing the results of this experiment with those of experiment I. In both instances no scavenging agent was used. The gold that received the higher irradiation level settled faster.

Because water vapor in all instances showed such a beneficial effect on the precipitation, the effect of water particles alone was also tested (experiments IX and X). However, the results of these experiments were not satisfactory and by far not as good as those obtained with the silicon tetrafluoride-water combinations. This clearly shows that the silicon tetrafluoride, and not the water, is responsible for the good scavenging effects obtained in experiments XI and XII.

Silicon tetrachloride was also investigated as a scavenging agent, because it does not yield toxic or as strongly corrosive hydrolysis products as does the silicon tetrafluoride. It was found to be operative but yielded considerably less satisfactory results than the silicon tetrafluoride. This again shows the outstanding place silicon tetrafluoride occupies as a scavenger for the purpose of this invention.

EXAMPLE II

Two parallel experiments were carried out, experiment I using 0.044 vol. percent of silicon tetrafluoride at room temperature together with 1.04 N sodium hydroxide at a relative humidity of between 90 and 100%, experiment II using the same conditions but only a relative humidity of 23%. These two experiments were compared with experiment XI of Example I in which a mixture of silicon tetrafluoride and water (relative humidity from 90 to 100%), without sodium hydroxide, was used as the scavenger. Also in these instances a gold wire was electrically exploded as in Example I, and the chamber was evacuated to 28 inches of Hg prior to the introduction of silicon tetrafluoride. The results of these experiments are compiled in Table II.

It will be obvious from the data below that the presence of sodium hydroxide did not have any beneficial effect on the scavenging efficiency. However, in the instance where the humidity was between 90 and 100% (experiment I), the precipitation results compared favorably

4
Table II

5	Radioactivity, Percent	Expt. I	Expt. II	Expt. XI of Example I
		Time, min.	Time, min.	Time, min.
10		Sodium Hydroxide, 0.044% SiF ₄ , 68° F., 90-100% R.H.	Sodium Hydroxide, 0.044% SiF ₄ , 68° F., 23% R.H.	Distilled Water, 0.044% SiF ₄ , 78° F., 90-100% R.H.
90		0.70	2.43	3.50
80		2.71	4.25	4.99
70		3.97	9.49	5.70
60		4.94	14.69	6.20
50		6.51	19.84	6.50
40		7.52	25.30	6.70
30		9.05	37.22	7.50
20		14.75	43.79	8.99
10		19.23	59.71	13.49

with those of experiment XI where no sodium hydroxide was used, this in particular in the first half of the precipitation procedure (up to a 50% precipitation). When the humidity was only 23%, it took three times as long to reduce the radioactivity by 50% as when the humidity was above 90%. Thus it proved to be advantageous to use a high humidity with the silicon tetrafluoride and sodium hydroxide to avoid harmful effects of hydrolysis products.

It will be understood that this invention is not to be limited to the details given herein but that it may be modified within the scope of the appended claims.

What is claimed is:

1. A process of decontaminating an atmosphere from radioactive particles suspended therein, comprising introducing silicon tetrafluoride into said atmosphere whereby said particles precipitate, and separating said particles from said atmosphere.
2. The process of claim 1 wherein water vapor is added to the atmosphere so that precipitation occurs in the presence of said water vapor.
3. The process of claim 1 wherein water vapor is added in a quantity of from 1.5 to 3 percent by volume of SiF₄.
4. The process of claim 1 wherein a neutralizing agent is added to the atmosphere to be treated together with the silicon tetrafluoride.
5. The process of claim 4 wherein the neutralizing agent is a sodium hydroxide solution of a concentration of from 1 to 2 M.
6. The process of claim 4 wherein the neutralizing agent is a sodium metasilicate solution of a concentration of from 1 to 2 M.
